UNITED STATES PATENT OFFICE.

JAMES H. RAND, JR., OF TONAWANDA, NEW YORK, ASSIGNOR TO ZENITH SYSTEMS
CORPORATION, OF TONAWANDA, NEW YORK.

CARD-INDEX SYSTEM

1,272,526.

Specification of Letters Patent. Patented July 16, 1918.

Original application filed September 18, 1915, Serial No. 51,439. Divided and this application filed February 16, 1917. Serial No. 149,181.

To all whom it may concern:

Be it known that I, JAMES H. RAND, JR., a citizen of the United States, residing at Tonawanda, in the county of Erie and State of New York, have invented a new and useful Improvement in Card-Index Systems, of which the following is a specification.

This invention relates to card index systems of the overlapping card type, and consists primarily in a series of cards having tongues so disposed that when the several cards of the series are assembled and nested, as hereinafter described, the cards will be interlocked by said tongues, and will also be supported and spaced one above another, with their margins exposed, by reason of the nested and interlocked relation of the several cards and tongues. These and associated features will hereinafter be more fully described and particularly pointed out in the claims.

This application is a division of application for U. S. Letters Patent filed by me September 18, 1915, Serial No. 51,439.

25 In the accompanying drawings, which illustrate certain embodiments of the invention:

Figure 1 is a face view, partly broken away, of several cards embodying the invention, mounted in a frame.

Fig. 2 is an elevation of the reverse side of the interlocked cards shown in Fig. 1.

Fig. 3 is a perspective view of one of the individual cards, but showing a slightly different position of the hinge.

Fig. 4 is a sectional view of a series of the cards interlocked.

Fig. 5 is a perspective view of a card of slightly modified form.

40 Fig. 6 is a sectional view of the card shown in Fig. 5.

Fig. 7 is a perspective view showing still another modification of the card.

In some of the more common card systems of the overlapping card type as heretofore used, the cards are supported by and hinged to bars or strips, which serve both as supports and spacers, said bars or strips being held at their ends in the guide channels of a suitable frame. In the present invention the overlapping cards are provided with tongues which support the cards one above another and space the cards relatively to each other, and which also interlock the

cards in such manner that when the cards are assembled no card can be removed from the series without first moving it out of interlocking engagement with other cards. This construction prevents the abstraction, either through accident or design, of any card from the series, dispenses with the necessity of relatively heavy and costly supporting and spacing bars, and, if desired, admits of forming the card with its supporting and spacing means out of an integral sheet of paper, cardboard, or the like. When the cards are mounted in a flanged frame they are provided with laterally extending projections to engage the guide flanges of the frame, but as such projections do not perform the functions of spacing and supporting the cards one above another, as do the supporting bars heretofore used, they may be made of comparatively light material such as the material of the card itself, since they are merely to prevent the cards from falling out of the frame. Each card is also preferably hinged in the manner hereinafter explained to facilitate inspection.

Referring first to the form shown in Figs. 1 to 3, A represents a frame of usual construction, having inwardly turned guide flanges *a* forming channels to receive the laterally extending projections of the cards. Each card *B* is provided with a tongue *b* formed by folding over one margin of the card and securing the fold to the body of the card by suitable means, such as a line of staples *c*. The free edge of the fold beyond the staples constitutes a single tongue, the base of which is determined by the fastening means *c*, spaced from the proximate edge of the card, while the tongue extends substantially flatwise of the card toward the opposite edge. The cards are nested and interlocked by inserting the margin of one card between the tongue and body of the next card. Although the tongues *b* are preferably made integral with the card bodies and folded over, they might be made of separate pieces *b*² of paper or other sheet material fastened to the card bodies, as shown in Fig. 5. When the several cards of a series are assembled the margin of each card *B* is nested between the tongue *b* and the body of the next adjacent card in the series. Thus the cards are spaced by said tongues relatively one to another with their margins

projecting beyond one another, as best shown in Fig. 1, and the cards are also relatively interlocked by said tongues. The base of each tongue, spaced from one edge 5 of the card, constitutes the line on which the card is supported by, and spaced relatively to, its neighbor.

Instead of mounting the cards in the frame as shown in Fig. 1, they might be mounted in reverse position as shown in Fig. 19 2, in which case the upper exposed margins instead of the lower margins, would be used for names or other indexed matter; or the 15 cards could be merely inverted top for bottom, with either the obverse or reverse side facing outward, in which case the overlapping cards would be upstanding instead of down-hanging.

To facilitate manipulation and inspection 20 of the cards, each is made with a hinge b' , connecting the portion of the card which carries the tongue b with the free portion or flap portion. The hinge is preferably made integrally of the card itself by means 25 of a crease, or other weakened portion, and is located in the body of the card within the area limited by the line of support passing through the base of the tongue or tongues, that is, the hinge is at or below said 30 line of support, so that the hinged part of the card may be swung on the relatively fixed part of the card which carries the tongue or tongues without moving or affecting the position of the tongues. In Figs. 1 35 and 2, the hinge b' is located in a line somewhat removed from the base of the tongues and just beyond or substantially coincident with the ends of the tongues, so 40 that no part of a card which is overlapped by a tongue will be swung on the hinge, a construction particularly advantageous when the cards are used in the position shown in Fig. 2.

The cards shown in Figs. 3 and 4 are 45 identical with those shown in Figs. 1 and 2 save that the hinges b^2 are located nearer to the base of the tongue than in the cards shown in Figs. 1 and 2.

The cards thus nested and interlocked 50 are supported and spaced by the tongues, and could be used in a suitable box or receptacle without other retaining means. When the cards are to be used in a vertical frame A, of the so-called visible index type, they 55 are provided with projections d extending laterally from the card and engaging the guide flanges a of the frame. These projections d are preferably formed of the same sheet material as and integral with the card 60 itself, or the tongue, and extend laterally from each end of that margin of the card which lies between the base of the tongues and the proximate edge of the card. The projection need not be of stout material like 65 the supporting and spacing bars of over-

lapping card index systems heretofore used, since they are required merely to prevent the cards from falling out of the frame while the weight of the cards upon one another is supported, and the spacing is effected, by the tongues.

In order to afford additional interlocking means, each projection d may be made wider in its vertical dimension than the distance between the base of the tongue and the proximate edge of the card, so that successive projections overlap one another under the guide flange a , as shown in Figs. 1 and 2, when the series of cards is assembled in the frame.

In the modifications shown in Figs. 5 and 6, the cards B^3 are identical with those shown in Figs. 3 and 4 except that the tongues b^3 are formed by separate strips of material secured to the cards instead of by folding over integral portions of the cards. The tongue strips b^3 can be made from the same kind of material as the cards or from any other suitable thin material.

In the modification shown in Fig. 7, the card B^4 , the folded over tongue b^4 and the fasteners c are substantially the same as the corresponding parts in Figs. 1 to 4. The projections for holding the card in the frame consist of the ends of a rod e , inserted in the loop of the fold between the fasteners c and the folded edge of the card. As these projections neither support the weight of the cards nor constitute the spacing means, the rod may be as light and slender as desired, and need not have any spacing devices at its ends as has heretofore been necessary.

The cards shown and described may have the reading matter or information written 105 or printed directly thereon, or separate cards or pieces of paper or the like bearing the written or printed matter may be secured in any suitable manner on the cards, in which case the cards B, etc., could be considered as holders for index cards or the like.

I claim as my invention:

1. In a card system, a series of overlapping cards, each having a tongue formed by 115 a strip of material extending crosswise of the card on one side thereof, means fastening the tongue between its edges to the card and determining the base of the tongue, the base of said tongue being spaced from one 120 edge of the card and the tongue extending from its base toward the opposite edge of the card, and one margin of each card being nested between the tongue and body of the next card in the series, whereby said 125 cards are interlocked and spaced by said tongues relatively to one another with their margins projecting one beyond another.

2. In a card system, a series of overlapping cards, each having a tongue formed by 130

- a relatively narrow strip of material extending crosswise of the card on one side thereof of adjacent one edge only of the card and having free ends adapted to engage a frame 5 for retaining the cards thereon, the base of said tongue being spaced from one edge of the card and the tongue extending from its base part way toward the opposite edge of the card, and one margin of each card being nested between the tongue and body of the next card in the series, whereby said cards are interlocked and spaced by said tongues relatively to one another with their margins projecting one beyond another. 10
- 15 3. In a card system, a series of overlapping cards, each having a tongue formed by a strip of material extending crosswise of the card on one side thereof and forming laterally extending projections at the ends 20 of the card adapted to engage a frame for retaining the cards thereon, means fastening the tongue between its edges to the card and determining the base of the tongue, the base of said tongue being spaced from one edge 25 of the card and the tongue extending from its base toward the opposite edge of the card, and one margin of each card being nested between the tongue and body of the next card in the series, whereby said cards 30 are interlocked and spaced by said tongues relatively to one another with their margins projecting one beyond another.
4. In a card system, a series of overlapping cards, each having a tongue formed by an integral portion of the card folded over and secured against one face thereof, the base of said tongue being spaced from one edge of the card and the tongue extending from its base toward the opposite edge of 40 the card, and one margin of each card being nested between the tongue and body of the next card in the series, whereby said cards are interlocked and spaced by said tongues relatively to one another with their margins 45 projecting one beyond another.
5. In a card system, a series of overlapping cards, each having a tongue formed by an integral folded portion of the card, means fastening the tongue between its edges to the body of the card and determining the base of the tongue, the base of said tongue being spaced from one edge of the card and the tongue extending from its base toward the opposite edge of the card, and one margin 55 of each card being nested between the tongue and body of the next card in the series, whereby said cards are interlocked and spaced by said tongues relatively to one another with their margins projecting one beyond another. 60
6. In a card system, a series of overlapping cards, each having a tongue formed by an integral portion of the card folded over against one face thereof and having ends 65 adapted to engage a frame for retaining the
- cards thereon, the base of said tongue being spaced from one edge of the card and the tongue extending from its base toward the opposite edge of the card, and one margin of each card being nested between the tongue and body of the next card in the series, whereby said cards are interlocked and spaced by said tongues relatively to one another with their margins projecting one beyond another. 70
7. In a card system, a series of overlapping cards, each having a tongue formed by a strip of material extending crosswise of the card on one side thereof, the base of said tongue being spaced from one edge of the card and the tongue extending from its base toward the opposite edge of the card, and one margin of each card being nested between the tongue and body of the next card in the series, whereby said cards are interlocked and spaced by said tongues relatively to one another with their margins projecting one beyond another. 75
8. In a card system, a series of overlapping cards, each having a tongue formed by a strip of material extending crosswise of the card on one side thereof, the base of said tongue being spaced from one edge of the card and the tongue extending from its base toward the opposite edge of the card, and one margin of each card being nested between the tongue and body of the next card in the series, whereby said cards are interlocked and spaced by said tongues relatively to one another with their margins projecting one beyond another, and a pair of laterally extending projections on each card adapted to engage a frame for retaining the cards 80 85 90 95
9. In a card system, a series of overlapping cards, each having a tongue formed by a strip of material extending crosswise of the card on one side thereof, the base of said tongue being spaced from one edge of the card and the tongue extending from its base toward the opposite edge of the card, and one margin of each card being nested between the tongue and body of the next card in the series, whereby said cards are interlocked and spaced by said tongues relatively to one another with their margins projecting one beyond another, and a pair of laterally extending projections on each card adapted to engage a frame for retaining the cards 100 105 110
10. A card for card systems having a tongue formed by a strip of material extending crosswise of the card on one side thereof, the base of the tongue being spaced from one edge of the card and the tongue extending from its base toward the opposite edge of the card, and one margin of each card being nested between the tongue and body of the next card in the series, whereby said cards are interlocked and spaced by said tongues relatively to one another with their margins projecting one beyond another. 115 120 125 130

edge of the card, and a pair of projections extending laterally from the ends of that portion of the card at which the tongue is located.

- 5 11. A card for card systems having a tongue formed by a relatively narrow strip of material extending crosswise of the card on one side thereof adjacent one edge only of the card, the base of the tongue being spaced 10 from said edge of the card and the tongue extending from its base part way toward the opposite edge of the card, the ends of said tongue forming laterally extending projections adapted to engage a frame.
- 15 12. A card for card systems having a tongue formed by a strip of material extend-

ing crosswise of the card on one side thereof, the base of the tongue being spaced from one edge of the card and the tongue extending from its base toward the opposite edge of the card, said card being provided with a hinge connecting that portion of the card carrying the tongue with the flap portion of the card, and a pair of projections extending laterally from the ends of that portion of 25 the card at which the tongue is located.

Witness my hand, this 30th day of January, 1917.
